UNITED STATES PATENT OFFICE

157,442

TRUCK BODY

Bernard Schwartzman, Chevy Chase, Md., and Worth C. Gatewood, Alexandria, Va.

Application January 9, 1948, Serial No. 143,624

Term of patent 14 years

(Cl. D14—3)

To all whom it may concern:

Be it known that we, Bernard Schwartzman and Worth C. Gatewood, both citizens of the United States of America, residing at Chevy Chase, Maryland, and Alexandria, Virginia, respectively, have invented a new, original, and ornamental Design for a Truck Body, of which the following is a specification, reference being had to the accompanying drawings, forming part thereof.

We claim:

The ornamental design for a truck body, as shown.

BERNARD SCHWARTZMAN.
WORTH C. GATEWOOD.
